(57) **CLAIM**

The ornamental design for a “gaming machine”, as shown and described.

DESCRIPTION

FIG. 1 is an isometric view of a gaming machine showing our new design.

FIG. 2 is a front elevational view thereof.

[FIG. 3 is a rear elevational view thereof.]

FIG. [4] 3 is a left side elevational view thereof.

FIG. [5] 4 is a right side elevational view thereof.

[FIG. 6 is a top plan view thereof.]

[FIG. 7 is a bottom plan view thereof.]

The broken lines shown are for illustrative purposes only and form no part of the claimed design.

1 Claim, 4 Drawing Sheets
